FOLDING CHAIR

Filed Dec. 2, 1930

Inventor
Axel Steen Stokby.
By
Attorney
Peter C. Bonney.

UNITED STATES PATENT OFFICE

AXEL STEEN STOKBY, OF JACKSON HEIGHTS, NEW YORK, ASSIGNOR TO LIDO FOLDING REST COMPANY, INC., OF NEW YORK, N. Y., A CORPORATION OF NEW YORK

FOLDING CHAIR

Application filed December 2, 1930. Serial No. 499,445.

This invention relates to folding chairs, and particularly to folding chairs adapted for use on beaches, lawns and the like.

The invention has for its object generally 5 an improved chair of the character indicated which is durable, efficient, can be readily folded into a compact package and is readily and cheaply manufactured.

More specifically it is an object to provide 10 a foldable frame for chairs of the character indicated which may be completely collapsed and folded on itself, but when set up is rigid and is self-locking so that there is no danger of collapsing when in use.

15 Other objects of the invention will in part be obvious and will in part appear hereinafter.

The invention accordingly comprises the 20 features of construction, combinations of elements, and arrangement of parts, which will be exemplified in the constructions herein-after set forth and the scope of the application of which will be indicated in the claim.

For a fuller understanding of the nature 25 and objects of the invention, reference should be had to the following detailed description taken in connection with the accompanying drawing, in which:

Fig. 1 is a perspective view showing one 30 form of folding chair embodying the invention;

Fig. 2 is a perspective view showing a modified form of collapsible frame which 35 may be employed in the practice of the invention;

Fig. 3 shows a folding chair of the character indicated in Fig. 1, provided with a canopy;

Fig. 4 is a perspective view showing the 40 frame of the chair when collapsed; and

Fig. 5 is a similar view showing the frame wrapped in the chair covering ready for transport.

Referring now to the drawing and particularly to Fig. 1, 10 denotes generally the frame of the chair which as shown when set up is generally rectangular in shape and is composed of articulated members or mechanical links which are relatively rigid and may be 45 made of any suitable material, for example

of wood, metal or tubing. The frame is so articulated that it may be readily collapsed, but when extended and set up on the ground in the position shown in Fig. 1, is adapted to support a flexible cover 11 which may be 55 of canvas or other suitable sheet material in order to provide a chair or reclining support for the beach or lawn.

In accordance with the present invention, the frame of the chair is articulated, so that 60 it may be collapsed in two stages, the first of which involves the folding together of two portions of the frame like the leaves of a book, while the second stage involves folding inwardly upon the frame members the up- 65 standing portions which remain after the first stage of folding is completed. To this end, the rectangular frame shown in Fig. 1 comprises side members 12, to which connecting members 16 are attached at their ends by 70 hinges shown at 17. Each of the side members has intermediate hinges 15 whose axes are at right angles to the axes of the hinges 17. The side members 12 are thus seen to 75 comprise two portions 13 and 14 which are preferably of the same length. Also it is 80 preferable to dispose the hinges both at 15 and 17 at one edge of the end portions of the members, so that when opened fully to the straight line position, the end portions abut 85 so as to block further opening movement. By placing the hinges at 15 on the front side of the frame, it is seen that the stresses imposed when in use, cause the upper portion of the frame to be biased in open position, thereby avoiding the danger of collapse 90 while in use.

The chair frame thus provided is adapted 95 to be used with one side resting on the ground and supported in an inclined position. 20 Supporting means are associated with the frame, which in the form shown in Fig. 1, comprise an auxiliary frame-portion hingedly connected to the main frame. Here, members 18 are hingedly connected to the members 14 with hinges parallel to those at 15. A ground reacting member 19 is hingedly 25 connected to the lower ends of members 18. The auxiliary frame in this construction is 30 thus similar to the upper portion of the main 35

frame, so that when folded together in the first stage, these portions move as the three pages of a book, the two members 16 and the member 19 being at the bottom. When the 5 upstanding portions 13, 14 and 18 are folded in on the bottom members in the second stage, the collapsed frame appears as shown in Fig. 4. The cover 11, is attached to the front of the frame-work in any suitable manner, 10 the said cover being preferably provided with an integral seat portion 20, to serve as a protecting means, when this chair is used on the beaches, or when on the ground. When the cover 11 has been removed and 15 the frame collapsed to the position shown in Fig. 4, it may then be used as a wrapper for the frame. To this end the frame when collapsed is laid on one end of the cover while spread out flat. It is then rolled into the 20 package shown in Fig. 5. In order that the cover may remain securely in this wrapped position, it preferably has snap-fasteners positioned as shown at 32. These fasteners 32 or other convenient fasteners may be used to 25 attach the cover to the member 16 when the back rest is in use.

In Figure 2 is shown a modified construction which differs from that shown in Figure 1, mainly in that the front side members 21, 30 21, are of a rigid construction, whereas the connecting members 22, and 23, are at the top and bottom respectively and have intermediate hinges at 24, their ends being hinged with axes at right angles to the intermediate 35 hinge, and thus serve as means for folding the device together.

The frame when in service position is supported by members 25, 25, which are connected to the front side members by hinges 40 at 26, and are provided with ground reacting portions 27, 27, in order to avoid sinking in soft ground, when the device is set up for use.

A cover similar to that shown in Figure 1, is attached to said frame in Figure 2, to 45 complete the device.

Whenever desired the said device may be provided with a canopy, as shown at 28 in Figure 3. Here the canopy is supported on another auxiliary frame, which is hinged at 50 the side to the front side members, as shown at 29. The axes of these hinges are so disposed that the canopy may be made to collapse at the front 30, or at the side 31, according to the position of the hinges for folding the 55 device together.

It is obvious that the present invention is not strictly limited to the form of construction shown herein, but applicant reserves the right to make all such minor changes and 60 modifications that may be well within the scope of this invention and the appended claim.

Having thus described my invention, what I claim as new and desire to secure by Letters 65 Patent of the United States, is:

A folding back rest, comprising a collapsible rectangular main frame consisting of connecting members and side members, each of said side members being divided into two portions by a hinge, hinges at the ends of said 70 connecting members, joining said connecting members to said side members and having axes at right angles to the axes of said first-mentioned hinges, supporting means, and hinges connecting said supporting means to 75 said side members and adjacent to and having axes parallel with said first-mentioned hinges, whereby said side portions and said supporting means are triple elements of a compound hinge.

Signed at New York city, in the county of New York and State of New York this 22nd day of November A. D. 1930.

AXEL STEEN STOKBY.
